[57] CLAIM

The ornamental design for a towel ring, as shown.

DESCRIPTION

FIG. 1 is a perspective view of a towel ring showing my new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a side elevational view taken from the right of FIG. 1, the side opposite being a mirror image thereof; and

FIG. 7 is a sectional view taken in the direction of the arrows on line VII—VII of FIG. 4.
